UNITED STATES PATENT OFFICE.

ARTHUR MENDE, OF NEW YORK, N. Y., ASSIGNOR TO ROLLIN M. MORGAN,
OF NEW YORK, N. Y.

GAS OR VAPOR LAMP.

SPECIFICATION forming part of Letters Patent No. 728,265, dated May 19, 1903

Application filed August 15, 1902. Serial No. 119,701. (No model.)

To all whom it may concern:

Be it known that I, ARTHUR MENDE, a citizen of the United States, residing in the city of New York, in the county of New York and State of New York, have invented certain new and useful Improvements in Gas or Vapor Lamps, of which the following is a specification.

This invention relates to gas or vapor lamps; and it consists substantially in the improvements hereinafter particularly described.

The invention has reference more especially to that class of gas or vapor lamps in which ordinary gas is combined with atmospheric air and consumed at one or more burners either for heating or illuminating purposes; and one of the principal objects of the invention is to provide a gas or vapor lamp of this kind in which perfect admixture of gas and air is had, resulting in a clear flame of great brilliancy and intensity.

A further object of the invention is to provide a gas or vapor lamp which is simple in the construction and organization of elements or parts thereof and one which is effective and reliable in use or operation.

The above and additional objects are attained by means substantially such as are illustrated in the accompanying drawings, in which—

Figure 1 is an enlarged perspective view, in part vertical section, of the gas and air burner employed in my improved gas or vapor lamp, and Fig. 2 is a side view of the lamp, on reduced scale. Fig. 3 is a side view of the main and auxiliary or pilot burners shown in Fig. 2.

Before proceeding with a more detailed description it may be stated that my improved gas or vapor lamp comprises a specially-constructed fitting, in the main body of which works a gas-admission cock or valve having a lateral port which may be made to register with a port communicating with the interior of a branch of the fitting, in which branch is screwed or otherwise fastened an end of a gas-supply pipe leading from any point of support therefor. Secured in the upper end of the main body of the fitting is a burner-tube having at the upper end thereof preferably

duplicate main burners for the combined gas and air, the said burner-tube having air-inlet openings and otherwise specially constructed, as hereinafter specifically described. Leading preferably from the sides of the branch of the fitting are duplicate small gas-tubes extending upwardly through and slightly above the main burners, the upper ends of which tubes constitute pilot or ever-lighted burners by which ignition of the gas mixture is effected at the main burners whenever the gas-supply is turned onto said main burners.

The gas-admission cock or valve is formed with a port for the operative end of a needle-valve for controlling the gas-supply to the burner-tube, the said gas-admission cock or valve being of special embodiment, and the said needle-valve is provided with special means for adjusting or regulating the same. The interior of said burner-tube constitutes practically a mixing-chamber for the gas and air, and inclosing the burner-fitting is a cage which supports an ordinary glass globe having a reflector at the top, and upon which globe is a chimney or tube surmounted by another reflector, all as will hereinafter fully appear.

Specific reference being had to the accompanying drawings by the designating characters marked thereon, A represents a specially-constructed fitting, the body a of which is hollow, as shown, and the inner surface of which is conical or tapering upwardly, as indicated at b, said fitting having a lateral upturned branch c, communicating with the interior of body a by means of a port d in the side of the latter. Screwing into or otherwise fitting the end of said upturned branch c is the lower end of an ordinary gas-supply pipe e, which may lead from a ceiling or other support, and snugly fitting within the hollow body a of the fitting A is a conical cock or plug-valve B, which is also preferably hollow, as shown, and is formed with a lateral port f, which may be carried into and out of register with port d, as desired, by simply turning the cock or valve B in one direction or the other, the said cock or valve being formed or provided at its lower end with a shank or stem g, which works or turns in an opening in a nipple or cap h, which is threaded externally to screw into the

lower end of the hollow body *a* of the fitting, as shown, and surrounding the said shank or stem is a spring exerting its tension between the said nipple or cap and the lower end of 5 the said cock or valve to constantly urge the latter upwardly within the said hollow body, so as to prevent leakage of gas from the fitting. The pressure of said spring may be increased or diminished by properly adjusting 10 the nipple or cap *h*, as is apparent. The said shank or stem *g* is provided with a central longitudinal opening, through which passes from beneath a needle-valve *C*, the upper pointed end *m* of which regulates the passage 15 of gas or vapor through a port *n* in the upper end of cock or valve *B*, the sides of said port being also conical. (See Fig. 1.) The lower portion *s* of said needle-valve is threaded to fit a threaded opening *s'* in the shank or stem, 20 the latter being formed or provided at its lower end with a key *10*, which may be taken hold of by the hand for the purpose of turning or manipulating the cock or valve *B* to turn on and shut off admission of gas to the interior 25 thereof. The lower end of the needle-valve is notched at *u* to receive the end of a screw-driver or other implement which may be conveniently employed to turn said needle-valve when desired to adjust the same.

30 The upper end of the body *a* of the fitting *A* is recessed and interiorly screw-threaded at *v* to receive the corresponding exteriorly-threaded lower end of a burner-tube *D*, provided around its lower portion with air-inlet 35 openings *w*, the said tube being surmounted by preferably duplicate main burners *E* and the interior thereof constituting a mixing-chamber for the gas and air passing to said burners. The location of the gas-exit 40 port *n* in the end of cock or valve *B* is such with respect to said air-inlet openings that the force of gas issuing from said port induces currents of air to enter such openings and mix with the gas in a manner quite apparent. Each of the said main burners is provided with a lateral projection *x* for receiving the lower end of the supporting-rod *y* of an ordinary incandescent mantle *11*, the said rods being secured in place by set-screws *z*, 45 as shown.

Fitting in a hollow plug *12*, projecting from each side of the upturned branch *c* of the fitting *A*, is the lower end of a small gas-tube *14*, said tubes leading upwardly through and 55 above the main burners from beneath, as shown, and the upper ends *16* thereof constituting auxiliary or pilot burners which may be kept constantly lighted to serve to ignite the gas mixture at said main burners whenever 60 a supply of gas is caused to flow thereto. Said auxiliary or pilot burners are constantly supplied with gas from the branch *c* of the fitting, which branch, as is understood, is in open communication with the gas-supply pipe *e*. Preferably I employ a valve *20*, working 65 in each of said plugs *12*, for cutting off the

passage of gas to the said pilot or auxiliary burners, if desired.

Screwing upon the lower externally-threaded end *25* of the body *a* of the fitting *A* is a ⁷⁰ collar or ring *26*, between the upper edge of which and a shoulder *27* on the body is clamped a cage or holder *30* for an ordinary glass globe *32*, the lower edge of which fits within a ring *33* on the upper edge of said cage or holder and is fastened by a set-screw *34*, the cage or holder being formed, preferably, all around with air-inlet openings *35*. Located at the upper part of the globe is a reflector *38*, which may be integral with or attached to a chimney or flue *40*, which also is preferably surmounted by a reflector *42*, suitable means *43* being provided above said reflector whereby the lamp structure may be suspended from any suitable support therefor. As thus constructed and organized it will be seen that my improved gas or vapor lamp is simple and effective and also that the same may be manufactured at comparatively small cost. ⁹⁰

It is apparent that I am not limited to the precise details of embodiment herein illustrated and described, since departures may be made therefrom coming within the scope of my invention. ⁹⁵

Having described my invention, I claim—

1. A gas or vapor lamp comprising a fitting having a hollow body formed with a lateral port adapted for communication with a gas-supply pipe, a rotatable hollow cock or valve ¹⁰⁰ working in said body and formed with a lateral port and an end port, a burner and supporting-tube therefor mounted on said body, said tube having inlets for air, a needle-valve working in said cock or valve for controlling the exit of gas from said end port, and means for operating the latter valve to carry the lateral port thereof into and out of registry with the lateral port of the fitting. ¹⁰⁵

2. A gas or vapor lamp comprising a fitting ¹¹⁰ having a hollow body formed with a lateral port and provided with a branch adapted for connection with a gas-supply pipe, a rotatable hollow cock or valve working in said body and formed with a lateral port and an end ¹¹⁵ port, a burner and supporting-tube therefor mounted on said body, said tube having inlets for air, and a needle-valve working in said cock or valve for controlling the exit of gas from said end port, and means for operating the latter valve to carry the lateral port thereof into and out of registry with the lateral port of the fitting. ¹²⁰

3. A gas or vapor lamp comprising a fitting having a hollow body formed with a lateral ¹²⁵ port adapted for communication with a gas-supply pipe, a rotatable hollow cock or valve working in said body and formed with a lateral port and a port in its upper end, a spring exerting upward pressure to said hollow cock ¹³⁰ or valve, a burner and supporting-tube therefor mounted on said body, said tube consti-

tuting a mixing-chamber and having inlets for air, a needle-valve working in said cock or valve for controlling the exit of gas from said end port, and means for operating the latter valve to carry the lateral port thereof into and out of registry with the lateral port of the fitting.

4. A gas or vapor lamp comprising a fitting having a conical bore and formed with a lateral port adapted for communication with a gas-supply pipe, a rotatable hollow conical valve working in said bore and formed with a lateral port and a port in its upper end, a burner and a supporting-tube therefor mounted on said fitting, said tube constituting a mixing-chamber and having inlets for air, a needle-valve working in said conical valve for controlling the exit of gas from said end port, and means for operating the latter valve to carry the lateral port thereof into and out of registry with the lateral port of the fitting.

5. A gas or vapor lamp comprising a fitting having a hollow bore and a lateral port and provided with a communicating branch adapted for connection with a gas-supply pipe, a rotatable hollow conical valve working in said bore and formed with a lateral port and an end port, a burner and a supporting-tube therefor mounted on said fitting, said tube constituting a mixing-chamber and having air-inlets, a needle-valve working in said conical valve for controlling the exit of gas from said end port, and means for operating the latter valve to carry the lateral port thereof into and out of registry with the lateral port of the fitting.

6. A gas or vapor lamp comprising a fitting having a hollow bore and formed with a lateral port adapted for communication with a gas-supply pipe, a rotatable hollow conical valve working in said bore and formed with a lateral port and an end port, a spring exerting upward pressure to said valve, a burner and a supporting-tube therefor mounted on said fitting, said tube constituting a mixing-chamber and having air-inlets, a needle-valve working in said conical valve for controlling the exit of gas from said end port, and means for operating the latter valve to carry the lateral port thereof into and out of registry with the lateral port of the fitting.

7. A gas or vapor lamp comprising a fitting having a hollow body formed with a lateral port and adapted for communication with a gas-supply pipe, a hollow cock or valve working in said body and formed with a lateral port and an end port, a burner and supporting-tube therefor mounted on said body, said tube having air-inlets, an additional tube also adapted for communication with the gas-supply pipe and extending in proximity to said burner and terminating in an auxiliary or pilot burner, a needle-valve working in said hollow cock or valve for controlling the exit of gas from said end port, and means for operating the latter valve to carry the lateral

port thereof into and out of registry with the lateral port of the fitting.

8. A gas or vapor lamp comprising a fitting having a hollow body formed with a lateral port and provided with a branch adapted for connection with a gas-supply pipe, a rotatable hollow cock or valve working in said body and formed with a lateral port and an end port, a burner and supporting-tube therefor mounted on said body, said tube having inlets for air, an additional tube adapted for communication with said gas-supply pipe and extending in proximity to said burner and terminating in an auxiliary or pilot burner, a needle-valve working in said hollow valve for controlling the exit of gas from said end port, and means for operating the latter valve to carry the lateral port thereof into and out of registry with the lateral port of the fitting.

9. A gas or vapor lamp comprising a fitting having a hollow body formed with a lateral port adapted for communication with a gas-supply pipe, a rotatable hollow cock or valve working in said body and formed with a lateral port and a port in its upper end, a spring exerting upward pressure to said cock or valve, a burner and supporting-tube therefor mounted on said body, said tube having air-inlets, an additional tube also adapted for communication with said gas-supply pipe and extending in proximity to said burner and terminating in an auxiliary or pilot burner, a needle-valve working in said hollow valve for controlling the exit of gas from said end port, and means for operating the latter valve to carry the lateral port thereof into and out of registry with the lateral port of the fitting.

10. A gas or vapor lamp comprising a fitting having a conical bore and formed with a lateral port adapted for communication with a gas-supply pipe, a rotatable hollow conical valve working in said bore and formed with a lateral port and a port in its upper end, a burner and a supporting-tube therefor mounted on said fitting, said tube constituting a mixing-chamber and having inlets for air, an additional tube also adapted for communication with said gas-supply pipe and terminating in an auxiliary or pilot burner, a needle-valve working in said hollow valve for controlling the exit of gas from said end port, and means for operating the latter valve to carry the lateral port thereof into and out of registry with the lateral port of the fitting.

11. A gas or vapor lamp comprising a fitting having a hollow body formed with a lateral port and provided with a communicating branch adapted for connection with a gas-supply pipe, a rotatable hollow conical valve working in said body and formed with a lateral port and an end port, a burner and a supporting-tube therefor mounted on said body, said tube constituting a mixing-chamber and having air-inlets, an additional tube adapted for communication with said gas-supply pipe and extending in proximity to

said burner and terminating in an auxiliary or pilot burner; a needle-valve working in said hollow valve for controlling the exit of gas from said end port, and means for operating the latter valve to carry the lateral port thereof into and out of registry with the lateral port of the fitting.

12. A gas or vapor lamp comprising a fitting having a hollow body formed with a lateral port adapted for communication with a gas-supply pipe, a rotatable hollow conical valve working in said body and formed with a lateral port and an end port, a spring exerting an upward pressure to the valve, a burner and a supporting-tube therefor mounted on said body, said tube constituting a mixing-chamber and having air-inlets, an additional tube also adapted for communication with said gas-supply pipe and extending in proximity to said burner and terminating in an auxiliary or pilot burner, a needle-valve working in said hollow valve for controlling the exit of gas from said end port, and means for operating the latter valve to carry the lateral port thereof into and out of registry with the lateral port of the fitting.

13. A gas or vapor lamp comprising a fitting having a hollow body and formed with a lateral port communicating with a gas-supply pipe, a rotatable hollow valve working in said body and formed with a lateral port and an

end port, said valve having a stem formed with an opening therethrough, and a spring surrounding said stem, an adjusting device for said spring, a burner and a supporting-tube therefor mounted on said body, said tube having air-inlets, and an adjustable needle-valve passing through the opening in the said valve-stem for controlling the exit of gas from said end port.

14. A gas or vapor lamp comprising a fitting having a hollow body and formed with a lateral port communicating with a gas-supply pipe, a rotatable hollow valve working in said body and provided with a lateral port and an end port, said valve having a stem formed with an opening therethrough, and a spring surrounding said stem, an adjusting device for said spring, a burner and a supporting-tube therefor mounted on said body, said tube having air-inlets, an adjustable needle-valve passing through said stem for controlling the exit of gas from said end port, a perforated cage or holder supported at the lower end of the said hollow body, a globe supported by said cage, and a flue or chimney and a reflector surmounting the globe.

ARTHUR MENDE.
